UNITED STATES PATENT OFFICE.

HENRY N. FELEY, OF EAST ORANGE, NEW JERSEY.

BOOK.

Application filed April 2, 1926. Serial No. 99,237.

The object of the invention is to provide an improved flat-opening check-book, or other book, constructed in an advantageous manner so that the book will lie open at any point. It is a serious inconvenience of ordinary check-books that they must be held open in order to keep the stubs from springing over onto the page to be written upon. According to the present invention the book is bound by means of shaft members passed through openings in the sheets and cover and provided with upset heads outside the cover, and spacer means on the shafts inside the cover, the spacer means being adapted to bear against the inner sides of the cover and keep the sheets free, that is to say, not tightly held or gripped. This, together with the fact that the openings through the separate sheets are materially larger than the diameter of the parts standing within them, permits the leaves to separate loosely at any point where the book is opened. As a further element of the complete combination, the sheets are provided with limp, creased zones adjacent and in front of the openings. Other features of the invention will become apparent as the specification proceeds.

In the accompanying drawings, forming part hereof:

Fig. 1 is a plan view of the book embodying the invention, a portion of the cover being broken away;

Fig. 2 is a longitudinal section through the book, open, the end portions being broken away because of lack of space;

Fig. 3 is a fragmentary sectional view on a larger scale, showing the closed condition;

Figs. 4, 5, 6 and 7 are detail sectional views of parts seen in Figs. 1, 2 and 3, before assembling;

Fig. 8 is a fragmentary sectional view like Fig. 3, showing another construction;

Fig. 9 is a side elevation of the rivet shaft of Fig. 8, with its prongs unbent;

Figs. 10 and 11 are sections of other parts seen in Fig. 9; and

Fig. 12 is a sectional view of a book showing still another modification.

The stiff-board cover of the book is marked 2, the hinges of the front and back parts of the cover are marked 3, and the binding strip of the cover is marked 4. The interior pad consists of separate leaves 5, not united by stitching, staples or gum.

Two large holes 6 are made through the rear portion of the collection of leaves, and corresponding holes 7 are made in the cover. The holes in both the leaves and cover may be made at the same time.

In the construction shown in Figs. 1 to 7, a tubular shaft 8 having a flange 9 is first inserted through each of the holes in one of the parts of the cover, the flange 9 being on the outside of the cover. A sleeve 10 having a flange 11 is then pushed over each of the shafts 8 so that the flange 11 bears against the inside of the cover. The end 12 of this sleeve is preferably contracted so as to clasp the shaft 8 frictionally and tensionally, holding the parts in preliminary assembly.

The two shafts 8 and two sleeves 10 having been inserted in this manner, the collection of sheets 5 are placed over the shafts 7 and sleeves. Then two sleeves 10^a, which are preferably shorter than the sleeves 10, also having flanges 11^a, and preferably having their ends 12^a contracted are pushed on over the protruding ends of the shafts until the ends 12, 12^a abut. The openings 7 in the other cover member are then passed over the ends of the shafts, this cover member resting on the flanges 11^a. A washer 13 is placed over the end of each shaft outside the cover, and the ends 14 are upset, forming a retaining head. The flanges 9 forming the heads at the opposite side of the book are preferably shaped under pressure in the dies as shown in Fig. 3.

It will be observed that the spacer means formed by the members 10, 10^a, the flanges 11, 11^a of which bear against the inner sides of the cover is so designed, and of such length, that the pressure exerted in clinching and upsetting the binder fastenings does not result in the leaves 5 being gripped or compressed at the binding. Instead they remain quite loose between the parts of the cover, which are held somewhat away from the leaves by the two-part spacer. The distance between the flanges 11, 11^a is somewhat greater than the thickness of the pad of leaves, or, at least, the leaves are only loosely held between these flanges. Furthermore, it will be seen that the holes 6 through the leaves are materially wider than the external diameter of the sleeves 10 within them. Consequently, when the book is opened at any point, the two sections of the collection

2
of leaves part freely as shown in Fig. 2, and there is no tendency for one side to flop over on the other.

Further contributing to this effect, the individual leaves are provided with limp zones 15, parallel with the binding, adjacent and in front of the holes 6; these zones being formed by numerous parallel creases or by other treatment tending to destroy the springiness of the paper at the regions where the leaves curve over the bends of the cover at the hinges 6, without seriously injuring the strength of the fiber.

In Fig. 8, the shaft, instead of being a tubular member is a split rivet 20, having a solid head 21 at one end. In the final operation of assembling, the prongs of this rivet are spread apart, or upset, and a cap is applied over and in engagement with them, forming a head. The spacer means inside the binding comprise a sleeve 22 and two separate end flanges 23 having collars 24 which are inserted into the ends of the sleeve, the whole encircling the shaft of the rivet.

In Fig. 12, the spacer means comprises a sleeve 30 and two washers 31 abutting the ends of the sleeve and forming flanges to bear against the inner sides of the cover and keep the leaves from being gripped.

Still other forms and modifications of the binding and spacing means are contemplated. Naturally, either of the forms of shaft may be used with any one of the formings of spacing means.

I claim.

1. In a book having covers and a plurality of sheets loosely mounted between said covers, a permanent binding comprising spacing means for spacing the covers in predeterminedly set relation to each other, said spacing means comprising a sleeve portion and end flanges, said flanges being spaced apart a distance greater than the thickness of the collection of sheets and interposed on either hand between the sheets and the cover, and a shaft passing through said spacing means and covers for permanently securing the covers and the collection of sheets, with the covers in the predeterminedly set relation to each other and the leaves loosely confined between said spacer flanges, said shaft being provided with a head on one end and an upset portion on its opposite end.

2. A book comprising, in combination, a cover and a collection of sheets perforated for binding, a shaft passing through the perforations in the sheets and cover and provided with heads outside of the cover, and spacer means surrounding the shaft

and extending from cover to cover and comprising a plurality of preformed sections provided with flanges, establishing for the sheets a space greater than the thickness of the collection of sheets, said spacer sections being in thrust relation to each other and adapted to bear with their flanges on either hand against the inner side of the cover and keep the sheets free, said spacer sections being adapted to maintain a certain predeterminedly set relation between the front and back covers.

3. A book comprising, in combination, a cover and a collection of sheets perforated for binding, a shaft passing through the perforations in the sheets and cover and provided with heads outside of the cover, and spacer means on the shaft inside the cover comprising two abutting sleeves having preformed flanges on their remote ends adapted to bear on either hand against the inner sides of the cover, the sheets being loosely confined between said flanges, and the covers tightly held between said flanges and the heads on the shaft, the parts all being permanently bound together.

4. A binding for a flat-opening book, comprising a shaft passing through openings in the sheets and cover and provided with heads outside the cover, and spacer means on the shaft inside the cover comprising two abutting sleeves having their abutting ends contracted to clasp the shaft and their remote ends flanged to bear against the inner sides of the cover.

5. The method of making a book which comprises associating a collection of sheets and the covers for the book and drilling openings therein, placing a headed shaft through an opening in one cover, passing a preformed spacer section over said shaft, the cover being confined between said section and the head on said shaft, passing said shaft and section through the openings in the collection of sheets, the shaft passing all the way through and extending beyond the sheets and the sleeve passing partway through the openings in the sheets, inserting another preformed spacer section through the openings in said sheets from the opposite side of the collection of sheets, said spacer sections abutting to establish a space for the sheets greater than the thickness of the collection of sheets; passing the extended head of said shaft through the other cover, and upsetting said extended end so that the covers are gripped between the ends of the shaft and the spacer sections while the leaves remain loose between the spacer sections.

HENRY N. FELEY.
